UNITED STATES PATENT OFFICE.

AUGUST F. MEISSELBACH, OF NEWARK, NEW JERSEY, ASSIGNOR TO A. F. MEISSELBACH & BROTHER, OF NEWARK, NEW JERSEY, A CORPORATION OF NEW JERSEY.

FISHING-REEL.

No. 845,805.

Specification of Letters Patent.

Patented March 5, 1907.

Application filed August 30, 1906. Serial No. 332,564.

To all whom it may concern:

Be it known that I, AUGUST F. MEISSELBACH, a citizen of the United States, residing in the city of Newark, county of Essex, and State of New Jersey, have invented certain new and useful Improvements in Fishing-Reels, of which the following is a specification.

This invention relates to that class of fishing-reels wherein the parts may be readily separated for inspection, cleaning, and lubricating; and the object of the same is to provide a tubular frame having either one or both of its head-plates removable, with the necessary bearing and click-springs secured in such head-plates.

Another object of my invention is to construct the frame of the fishing-reel of pressed or drawn metal, so that the tubular body and one of the head-plates may be made integral; and the second head-plate also of drawn or pressed metal, whereby the entire framework of the reel may be made to consist of but two parts.

A further object of my invention is to provide heavy and light click-springs and means for securing the same in position, so that when in operation the line which is wound upon the reel or spool may be fed out or wound up with varying degrees of strain thereon.

A further object of my invention is to provide an adjustable cap-screw, whereby the tension upon the spool-spindle may be adjusted to varying degrees as desired.

A further object of my invention is to provide an improved fastening for the head-plates in the end rings, so as to draw the head-plate into fixed position upon the end ring of the frame without unnecessary pressure upon the head-plate, which ordinarily would result in the distortion of the frame.

In carrying out my invention I make use of the structure illustrated in the accompanying drawings, in which—

Figure 1 is a side view of the reel complete. Fig. 2 is a horizontal section showing the various parts in position. Fig. 3 is an end view looking into the cup-shaped frame with the head-plate and spool removed; and Fig. 4 is an end elevation of the head-plate, showing the gear in position.

Similar letters of reference refer to like parts throughout the specification and drawings.

The frame of the reel consists of the tubular body *a* and the head-plate *d*. The body *a* and head-plate *d* are integral, the body being formed by drawing the margin of a disk of metal into the tubular shape, as shown. In this process of drawing the body *a* from such disk it is found that the portion of disk forming the head-plate is left of substantially its original thickness, while the drawn margin or body *a* is somewhat thinner than the head-plate. When the openings *a'* are cut into the body, the head-rings *b* and *c* are formed, as hereinafter described. Centrally secured in the head-plate *d* is the bushing *e*, interiorly screw-threaded and cylindrical upon its projecting surface. The bearing-plug *f* is screwed into the bushing *e*, as shown. Said plug is provided with the sleeved or cup-shaped cap *g*, knurled at its outer margin to form a gripping-surface for the fingers when adjusting the bearing, while the sleeve *g'* of the cap is longitudinally slit, as shown, into the spring-fingers *g''* to frictionally engage the exterior surface of the bushing *e*, and thereby prevent the accidental disarrangement of the adjusted bearing.

The journal *h'* of the spool-spindle *h* enters the bearing-plug, as shown, and when the opposite end of the spindle is supported, as hereinafter described, the bearing-plug *f* may be so adjusted in the bushing *e* as to exert varying pressures upon the end of the spindle.

Slidingly mounted in the radial slot *i* in the head-plate *d* is the pivoted click *k*, which consists of the exterior operating-knob *k'*, the shank *k''*, which is located in the slot *i*, and the arrow-shaped click-point *k''*. The point *k''* is held in position by the differential click-springs *l* and *l'*, which are secured to the head-plate *d* by means of the bridge-piece *m*. The springs *l* and *l'* are of different sizes and strengths, and thereby resist with differential pressure the swinging of the click *k* out of radial position. The points of the springs are upturned, so as to bear upon opposite sides of the click *k*, either in the position shown or when the click is in operative position, with its point in engagement with the click-wheel *o'*, herein-after described, when the springs rest in the notches *k''*.

The bridge-piece *m* is provided with two depressions *m'* on its under side of the proper shape to receive the bent ends of the springs *l* and *l'*. Conical dowel-holes *m''* are also provided in said bridge-piece *m* to receive the

conical dowels secured in the head-plate *d* for the purpose of properly centering the bridge-piece *m*, and thereby secure the proper pressure of the springs *l* and *l'* upon the click *k*. 5 A single screw *m*³ is sufficient to secure the bridge-piece *m* to the head-plate.

Secured to the head-ring *b* in any convenient manner is the removable head-plate *n*, which is flanged, as shown, and extends without 10 in said head-ring. This head-ring is provided with the usual spindle-bearing *n'*, crank *n*², and gear *n*³. I prefer, however, to secure the head-plate to the head-ring by the novel means illustrated. The head-ring *b* is 15 provided with a series of open slots *b'*, countersunk at their inner ends, as shown at *b'*. These slots are located around the head-ring in diametrical pairs to receive the screws *n*⁴, diametrically located in the flange of the head- 20 plate *n*. This permits of a ready adjustment of the head-plate into various positions, and when the screws *n*⁴ are screwed home the conical under sides of their heads will take into the countersunk ends of the slots *b'*, and thus 25 draw the plate into position and securely hold it in place.

The spool *o* is of the usual construction, having the journals at the spindle ends, as shown, to be carried by the bearing-plugs *f* 30 and *f'*. The spindle is further provided with the pinion *o'* to mesh with the drive-gear *n*³ and the click-wheel *o*² for engagement with the click *k*.

The frame-body *a* is cut out, as shown, to 35 form the openings *a'* for the passage of the fish-line, leaving the bars *a*² connecting the head-rings *b* and *c*. The metal from the under openings is cut away in such a manner as to leave the reel-plate *a*³ with its feet *a*⁴ integral with the corresponding bar *a*², by which 40 the reel is secured to the fishpole in the usual manner.

I do not wish to limit myself to the making of the tubular body *a* and its head-rings *b* and *c* integral with the head-plate *d*, as such head-plate may be made separable and secured to the corresponding head-ring in the same manner as the other head-plate is secured to its head-ring. 45

50 In Fig. 4 I have shown a bridge-piece *p* secured to the head-plate for carrying the gear-bearing of the gear *n*³. This bridge-piece *p* has the centering dowel-holes to receive the dowels *p*² in the head-plate, and the bridge-piece is secured to the head-plate by means of the screws *p*³, the heads of which are upon the outside of the head-plate.

Ordinarily the head-rings *b* and *c* are of the same diameter as the rest of the tubular body *a*; but under certain circumstances I 60 may expand the head-rings *b* and *c*, as shown in the drawings, and under such conditions I find that the frame possesses added strength and is less liable to distortion, while at the 65 same time a neater appearance is given to the

completed structure. However, I do not desire to confine myself to either one or the other forms, inasmuch as the gist of my invention resides in the construction of the tubular body and one integral head-plate formed by 70 drawing or pressing a disk blank into a cup shape. This construction affords a great saving in time, labor, and expense over previous methods of construction, wherein the parts of the reel-frame were constructed of 75 separate pieces carefully fitted together.

The process of making a frame has been reduced to a single step, or at most two steps, where the expanded head-rings are used.

It will thus be seen that I have produced 80 a fishing-reel embodying all of these features, which practically makes it what may be termed a "three-part reel"—that is, a reel which when taken apart consists of only the three parts—namely, the body, the spool, 85 and the head-plate carrying the crank and driving-gear.

I claim—

1. A fishing-reel having a tubular frame provided with expanded head-rings. 90

2. A fishing-reel having a tubular frame provided with integral expanded head-rings and a head-plate integral with one of said expanded head-rings.

3. A fishing-reel having a tubular frame 95 provided with expanded head-rings, a head-plate and a reel-plate, said parts being integral with said frame.

4. A fishing-reel having a tubular frame, expanded head-rings at each end of said frame, a head-plate integral with one of said head-rings and a separate head-plate removably secured to the other head-ring. 100

5. A fishing-reel comprising a frame, head-plates secured to said frame, bearings in said 105 head-plates, a spool inclosed in said frame and journaled in said bearings, a click-wheel secured to the spindle of said spool, a slidingly-pivoted click mounted upon the adjacent head-plate and a pair of differential 110 springs mounted in said head-plate to bear upon said click.

6. A fishing-reel provided with a head-plate, a bearing in said head-plate, a spool journaled in said bearing, a click-wheel secured to the spindle of said spool, a pivoted click slidingly mounted in said head-plate for engagement with said click-wheel and differential springs secured to said head-plate to bear upon the opposite sides of said click. 115

7. The combination in a fishing-reel, of a head-plate, a pivoted click slidingly mounted therein, differential springs secured to said head-plate to bear upon opposite sides of said click. 120

8. In a fishing-reel, the combination of a head-plate with a spool-bearing therein, said bearing comprising an internally-threaded bushing centrally secured to said head-plate, a bearing-plug screwed into said bushing, 125

said bearing-plug being provided with a cup-shaped tension-guard at its outer end, a series of slits in said guard, whereby said guard is made to grip the exterior surface of said bushing.

5 9. A tension-bearing for fishing-reels, comprising a cylindrical internally-threaded bushing, a bearing-plug screwed into said bushing, a slit cup-shaped head secured to said plug, the sleeve portion of said head adapted to frictionally engage the exterior surface of said bushing.

10 10. A head-plate fastening for fishing-reels, comprising a head-plate and a head-ring designed to fit one within the other, a pair of 15 open slots diametrically located in one of said parts, said slots being countersunk at their inner ends, a pair of screws diametrically located upon the other part, the heads of said 20 screws being conical on their under sides and adapted to fit the countersunk portions of said slots.

11 11. A head-plate fastening for fishing-reels, comprising a head-plate member and a 25 head-ring member, a series of open-ended slots diametrically located in pairs upon one of said members and countersunk at their inner ends, a pair of screws having the under sides of their heads conical and diametrically 30 located in the other member and adapted to fit said countersunk slots.

12. A tension-bearing for fishing-reels, comprising a cylindrical internally-threaded bushing, a plug screwed into said bushing, a cylindrical spindle bearing in said plug, a 35 knurled cap secured to the head of said plug, a slotted sleeve upon said cap adapted to frictionally engage the exterior of said bushing.

13. A fishing-reel comprising a reel-frame, 40 composed of a head-plate and a drawn tubular body integral with said head-plate, and a second head-plate detachably secured to the open end of said body, a spool mounted in bearings carried by said heads respectively 45 and operating mechanism secured to one of said heads.

14. A fishing-reel comprising a reel-frame, composed of a head-plate and a drawn tubular body integral with said head-plate, and a 50 second head-plate detachably secured to the open end of said body, a spool mounted in bearings carried by said heads respectively and operating mechanism secured to said second or detachable head.

55 This specification signed and witnessed this 27th day of August, 1906.
